UNITED STATES PATENT OFFICE.

GEORGE HAMMER, OF OAKLAND, CALIFORNIA, ASSIGNOR TO HAMMER-BRAY COMPANY, OF OAKLAND, CALIFORNIA, A CORPORATION OF CALIFORNIA.

COOKING TOP FOR STOVES.

Application filed December 29, 1923. Serial No. 633,364.

My invention relates to a cooking top for stoves in which the top gas-burners are positioned in a vented chamber whose upper side is formed by said top.

5 An object of the invention is to provide a stove top of the character described which is formed with an aperture extending practically over the entire burner chamber and in which there is adapted to be fitted either 10 a closed top or grate top that is arranged to be supported by the remainder or fixed portion of the top.

The invention possesses other objects and features of advantage, some of which, with 15 the foregoing, will be set forth in the following description of the preferred form of my invention which is illustrated in the drawings accompanying and forming part of the specification. It is to be understood 20 that I do not limit myself to the showing made by the said drawings and description, as I may adopt variations of the preferred form within the scope of my invention as set forth in the claims.

25 Referring to said drawings:

Figure 1 is a plan view of a stove showing the cooking top of my invention.

Figure 2 is a vertical sectional view of the stove taken on the line 2—2 in Figure 1.

30 Figures 3 and 4 are top views of two forms of separable portions of the cooking top.

While it has been demonstrated that gas stoves having closed tops above the top burners have many advantages over stoves 35 equipped with the usual grate top, users of gas stoves have been slow to purchase the former style of stove both on account of its novelty and on account of its greater first cost. In the manufacture and sale of closed

40 top gas stoves, I have found that by providing the portion of the top above the burner chamber with a closed top section which may be readily replaced by a grate top section of the same size, thereby providing for either

45 style of stove top at will, that the users of gas stoves are encouraged to purchase such a stove in preference to one adapted only for one style of cooking top. I therefore do not form the top in one piece extending over 50 the whole stove-top area, as is usual, but, rather, provide an aperture in the top above the burner chamber in which sections of different kinds may be fitted and held. In this manner I provide for a stove top of either

55 type with the same stove structure so that

the preferred type of top may be used therewith.

The stove top 6 of my invention comprises fixed and removable sections 7 and 8, the latter being positioned above the burner 60 chamber 9 of the stove 11. To provide for the mounting of the removable section 8, I form in the fixed top section 7 a rectangular aperture having the edges 12 thereof parallel to and positioned slightly inwardly of 65 the sides of the burner chamber. As here shown the lower portion of the edge 12 is provided with an inwardly extending flange portion 13 whereon the section 8, which has an area substantially equal to that of the 70 aperture, is adapted to be supported when fitted in the aperture. Preferably provided in the section 8 are removable lids 14 positioned directly over the burners 16 whereby removal of a lid will allow the placing of a 75 cooking utensil directly over the burner.

Since the chamber 9 is thus normally closed on top by means of the fixed and removable top sections, I provide for the venting of the gaseous products of combustion 80 by providing a vent 17 in the rear wall of the chamber. In this manner, the heated and gas laden air is removed at the rear of the stove and is thus prevented from escaping at the front of the stove. If for any 85 reason the user of the stove of my invention desires use of a top of other form than that of the section 8, replacement of this section by another such as the grated section 19 here shown may be readily effected, thus making 90 the stove convertible to a wide variety of top equipment and uses.

I claim:

1. In a stove of the character described, a fire box for solid fuel, a top-gas burner chamber separated from the box by a common side wall, a one-piece cooking top arranged over said box and chamber and having integral portions thereof overlying the top edges of the front and side walls of 100 said box and chamber including said common side wall and defining openings smaller in area than the associated box and chamber, top-sections provided with lid receiving perforations and removably fitted in said 105 openings, and lids fitting in said perforations of said top sections.

2. In a stove of the character described, a fire box for solid fuel, a top-gas burner chamber separated from the box by a com- 110

mon side wall, a cooking top arranged over said box and chamber and having integrally related portions thereof overlying the top edges of the front and side walls of said box and chamber including said common side wall and defining openings smaller in area than the associated box and chamber, and top sections removably fitted in said

openings, the top section over said chamber provided with lid receiving perforations, and lids fitting in said perforations. **10**

In testimony whereof, I have hereunto set my hand at Oakland, California, this 3rd day of December, 1923.

GEORGE HAMMER.
